US0D1079546S

(12) **United States Design Patent** (10) **Patent No.:** **US D1,079,546 S**
(45) **Date of Patent:** **** Jun. 17, 2025**

(54) **AUTOMOBILE**

(71) Applicants: **Hyundai Motor Company**, Seoul (KR); **Kia Corporation**, Seoul (KR)

(72) Inventor: **Yu Jun Kim Jin**, Seoul (KR)

(73) Assignees: **Hyundai Motor Company**, Seoul (KR); **Kia Corporation**, Seoul (KR)

(**) Term: **15 Years**

(21) Appl. No.: **35/521,410**

(22) Filed: **Dec. 21, 2023**

(80) **Hague Agreement Data**

Int. Filing Date: **Dec. 21, 2023**

Int. Reg. No.: **DM/234329**

Int. Reg. Date: **Dec. 21, 2023**

Int. Reg. Pub. Date: **Jun. 21, 2024**

(30) **Foreign Application Priority Data**

Aug. 17, 2023 (KR) 30-2023-0031939

(51) **LOC (15) Cl.** **12-08**

(52) **U.S. Cl.**

USPC **D12/91**

(58) **Field of Classification Search**

USPC D12/82, 84, 86, 87, 88, 89, 90, 91, 92, D12/93, 94, 96, 97, 98, 99, 163, 164, D12/165, 166, 167, 169, 170, 171, 172, D12/173, 190, 196; D21/533, 548, 552, D21/561

CPC B62D 25/00; B62D 25/06; B62D 25/08; B62D 33/00; B62D 35/00; B62D 31/00; B62D 31/003; B62D 31/02; B62D 47/00
